UNITED STATES PATENT OFFICE.

JOHN R. SEXTON, OF LA JUNTA, COLORADO.

HUB LINER.

Application filed July 2, 1926. Serial No. 120,123.

My invention relates to a floating hub liner for use intermediate of the journal-boxes and the wheels and more particularly for use intermediate of the journal-boxes 5 and the wheels of locomotives.

The invention has for its object the provision of a liner which may be readily put into place and equally as well removed and replaced when occasion requires without 10 necessity of disturbing or dismantling any of the running gear or adjacent elements of the locomotive; the invention, therefore, obviating the rather laborious and expensive methods at present employed.

15 The objects and advantages of my invention will all be thoroughly comprehended from the detailed description of the accompanying drawing, wherein—

Figure 1 is a vertical sectional view of one 20 end of a journal and journal-box; a portion of the journal and wheel being broken away and a part of the liner shown in elevation.

Figure 2 is a vertical sectional view taken substantially on the line 2—2 of Figure 1 25 looking in the direction of the arrows.

Figure 3 is a cross-sectional view taken on the line 3—3 of Figure 2.

Figure 4 is a detail perspective view of the non-assembled liner.

30 In the particular exemplification of the invention, a portion of the journal is indicated at 10 provided with the usual journal-box shown at 11, while the outer end is provided with the wheel 12 mounted on the 35 journal in accordance with the usual practice in locomotive construction; the journal-box being provided with the lubricating cellar shown at 13.

Hub liners as heretofore generally constructed and employed have been cast or riveted on the face of the journal-box, namely intermediate of the journal-box and the inner side of the hub of the wheel and therefore at inaccessible points. As a result, 45 great difficulty is encountered in applying and replacing these liners while the wheels and journal-boxes are in assembled relation. Such constructions involve great time and labor both in application and in renewal; 50 necessitating the placing of the locomotive over a "drop pit" in order that the wheels and journal-boxes may be lowered, or some means employed for lifting the locomotive off the wheels. Such operations, as is apparent, are quite expensive and require great 55 loss of time and labor.

My improved liner is of a construction which can be readily and quickly applied without disturbing or dismantling any part of the locomotive and therefore without such 60 loss of time as heretofore encountered.

My improved liner provides an anti-friction bearing face or surface which is intended to "float" or be loosely mounted on the journal and therefore free to revolve 65 thereon independently of any other part. The floating anti-friction liner, which is generally indicated at 14, consists of a pair of semi-annual complementary members 15 and 16 having tongue and groove relation or 70 connection with each other. That is to say, the section 15, in the particular exemplification, is provided with the transverse or radial grooves 17, 17, while the ends of the section 16 are provided with the transverse 75 tongues 18 which are adapted to fit into the grooves 17. The two sections 15 and 16 when properly assembled provide an annular member having wide bearing faces 19 disposed intermediate of the journal-box 11 80 and the inner side of the hub of the wheel 12.

The outer perimeter of the sections 15 and 16 are each provided with a circumferential groove 20 which is adapted to receive a constricting band or encircling rod 85 21. One end of this band or rod is formed in the shape of a hook or lug as shown at 22, see Figure 2, adapted to fit into a socket 23 formed in section 16; the hook or lug 22 firmly anchoring the band or rod in place. 90 The band is preferably formed to fit into or be seated in the circumferential groove 20 when the two sections 15 and 16 are assembled in matching relation; the band 21 being of length sufficient to extend entirely 95 about the two sections and somewhat beyond the socket 23 and therefore with the ends of the band or rod in lapping relation.

The section 16, at a point slightly beyond the socket 23, is provided with a radially 100 disposed shoulder 24. The groove 20 also extends through the shoulder 24 and is preferably made deeper at this point so that the ends of the band or encircling rod may be in lapping relation as shown in Figure 2. 105

The free end of the band or rod 21 is preferably threaded to receive nuts 25 and a washer 26 which rests on the slotted or grooved shoulder 24. It is obvious that by screwing nuts 25 down onto washer 26, the band or rod (which preferably seats entirely within circumferential groove 20) causes the 110

sectors or liner elements to be firmly clamped together and that the hook end 22 of the band or rod will also be held in its socket against accidental removal. On the other 5 hand, removal of the liner may be readily accomplished by simply unscrewing nuts 25, allowing the rod or encircling band to be removed, which permits the segmental sections of the liner to be separated; the application of the liner likewise being easily 10 accomplished without removing or disturbing any of the running gear.

As my improved liner is intended to "float" about the journal, the sector section 15 15, at a point intermediate of its ends, like the section 16, is also provided with a radially extending shoulder 24 which is likewise provided with a groove 20 therethrough for the encircling rod or band 21. 20 As is apparent by having both sections substantially identical in general configuration, they will balance each other and thus permit the "floating" action of the liner.

With my improved liner, free to "float" 25 or revolve about the journal, it is apparent that the entire flat bearing surfaces are permitted to come into play between the hub of the wheel and the journal-box; and while I have shown the liner composed of two sections or segmental sections, it is apparent 30 that any number may be employed if desired and that changes in other details may be made without, however, departing from the spirit of my invention.

35 What I claim is:

1. A hub liner comprising a plurality of flat sided segmental plates arranged in abutting circumferential relation and adapted to fit about a journal, said plates being grooved 40 circumferentially on the outer perimeters, an encircling element disposed about the plates in said groove, at least one of said plates being provided with a socket intersecting said groove and with a radially disposed shoulder on each side of said circumferential groove, said socket being adapted 45 to receive one end of the element while the shoulders are adapted to receive the other end of said element to hold the same in place, the relation between the socket and shoulders being such that the ends of the element 50 will lap each other.

2. A hub liner comprising a plurality of flat sided segmental plates arranged in abutting circumferential relation and adapted to fit about a journal, said plates being grooved 55 circumferentially on the outer perimeters, an encircling resilient element disposed about the plates in said groove, at least one of said plates being provided on its perimeter with a radially disposed projection adapted 60 to receive one end of said element and with a socket intersecting said groove adapted to receive the other end of said element,

the relation between the projection and 65 socket being such that the ends of the element will lap each other, and adjustable means for securing said end of the element to said projection.

3. A hub liner comprising a pair of flat 70 sided segmental plates arranged in abutting circumferential relation and adapted to fit about a journal, both plates being grooved circumferentially on the outer perimeters and each provided on its periphery with 75 a radially disposed shoulder whose outer perimeter tapers toward the periphery of the plate, the radial faces of said shoulders being diametrically opposite each other in the same horizontal plane, while the tapered 80 perimeters of the shoulders are disposed on opposite sides of said plane, said shoulders being grooved in alignment with said circumferential groove, at least one of said plates having a socket intersecting the circumferential groove, a resilient element encircling said plates and seated in said circumferential groove, one end of said element being seated in said socket while the other 85 end extends to said shoulder, and adjustable 90 means for clamping said last end to said shoulder, the relations between the socket and shoulder being such that the ends of said element will lap each other so as to hold the first mentioned end in said socket. 95

4. A hub liner of the character described, comprising a plurality of flat sided segmental plates arranged in abutting relation and adapted to fit about a journal, all of said plates being grooved on the outer perimeters, one of said plates having a radially disposed socket on its outer perimeter and a radially disposed shoulder on its outer perimeter at a point adjacent to the socket, and an encircling element adapted to seat in the circumferential groove of the assembled plates, one end of the element being inserted in said socket while the other end laps the end in the socket and is threaded, said last mentioned end terminating above said shoulder and provided with a nut threaded thereon. 100 105 110

5. A hub liner of the character described, comprising a plurality of flat-sided segmental sections, the radial edges of the sections having interlocking relation with each other, the circumferential edges being grooved, at least one of said sections having a radially disposed projection disposed on each side of the groove, and a socket on its outer perimeter, an encircling band adapted to fit 115 into said groove, one end of the rod being of hook-form to engage in said socket while the other end is threaded and is disposed between said projections, and means threaded onto the threaded end of the band and engaging said projections. 120 125
